(57) **CLAIM**

The ornamental design for night vision goggles, as shown and described.

DESCRIPTION

FIG. 1 is a front and top perspective view of the night vision goggles showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front and top perspective view of the night vision goggles in a state of use; and,

FIG. 10 is an enlarged detailed view taken from the oval area **10** in FIG. 1.

The dash-dash broken lines in the drawings depict portions of the night vision goggles and form no part of the claimed design. The dot-dash broken lines in the drawings demarcate the boundaries of the enlarged view and form no part of the claimed design.
